Inventor:
Arthur Francis Berry,
by *Albert S. Davis*
His Attorney.

UNITED STATES PATENT OFFICE.

ARTHUR FRANCIS BERRY, OF LONDON, ENGLAND, ASSIGNOR TO GENERAL ELECTRIC COMPANY, A CORPORATION OF NEW YORK.

ELECTRIC HEATING DEVICE.

1,378,515.

Specification of Letters Patent.

Patented May 17, 1921.

Application filed December 26, 1917, Serial No. 208,782. Renewed September 8, 1920. Serial No. 409,032.

To all whom it may concern:

Be it known that I, ARTHUR FRANCIS BERRY, a subject of the King of Great Britain, residing at London, England, have invented certain new and useful Improvements in Electric Heating Devices, of which the following is a specification.

This invention has reference to electrical heaters of the kind comprising perforated 10 plates or grids and bare resistance elements arranged beneath the same, and designed for heating or boiling water, for cooking and the like purposes, and it has for its object the provision of electrical heating 15 apparatus of this kind having greater efficiency, utility and durability than such apparatus as heretofore constructed.

For this purpose an electric heater made in accordance with my invention comprises 20 a metal plate having comparatively large openings separated by ribs or bars, and a bare resistance element that may be bent to a coiled, zig-zag or equivalent shape and is carried by and below the plate by holders of 25 insulating material secured to the ribs or bars which are constructed in such a manner as to shield the holders and adjacent portions of the resistance element from contact with liquid that may boil over from the vessel being heated, or which may become spilled therefrom in any way, so that deterioration of the insulating quality of the holders and rapid destruction of the holders and of the adjacent portions of the resist- 30 ance element shall be prevented and the efficiency and durability of the heating unit maintained. The resistance element may be connected at different points along its length to terminals combined with a switch so that 40 one, two or more sections of the element may be used at will to vary the heating effect produced, to suit requirements.

In the accompanying illustrative drawings, Figure 1 is a plan view of an electric heating device embodying my invention; 45 Fig. 2 is a section on the line 2—2 of Fig. 1; Fig. 3 is a section on the line 3—3 of Fig. 2; Fig. 4 is a view similar to Fig. 2, but partially in elevation showing a slightly modified form of support for the heating element; Fig. 5 is a detail view of a section of an insulating supporting strip and Figs. 6, 50 7 and 8 are detail views of modifications.

Referring now to the drawings, a plate 10 55 is provided with openings 11 which are pref-

erably sector shaped and separated by ribs 12. A bare resistance element 13 is supported beneath the plate by the ribs, from which the same is insulated. The resistance element which may be helically wound, is 60 formed into several convolutions which may be unevenly spaced apart as described in my British Patent #4672 of 1909, so as to insure the plate being uniformly heated. The resistance element is supported by insulating 65 strips 14 vertically disposed and preferably formed of mica. These strips are fixed in recesses 15 formed on the underside of the plate beneath the ribs.

The strips are preferably secured in position by wedges 16 (see Fig. 3) one on either side of the strip, which are also formed of insulating material. In the form of my invention shown in Fig. 5, each insulating strip is composed of two separate pieces provided with registering holes 17 in which the resistance element is disposed. In order to insert the resistance element sidewise into these holes, slits 18 are provided which extend from the holes to the lower edge of the 80 strips and in order to lock the resistance element in position, the slits in the two pieces leading to the opening are angularly arranged. Instead of arranging the slits in the strip at the lower edge of the piece as 85 just described, they may be arranged in the upper portion as shown in Fig. 6. In order to prevent any liquid or other material that is being treated on the plate from coming into contact with the members which support the resistance element, flanges 19 are 90 provided beneath the plate at the inner and outer portions of the supports from which the liquid may drip.

Figs. 7 and 8 show a modified arrangement in which each of the two strips of mica are formed with reversely arranged slots 20, the inner holes of which are curved and are armed with semi-circular metal guards 21. The arrangement is such that after the convolutions of the resistance element have been 95 placed in the slots when the strips of mica are apart, the strips are then brought together with the slots registering as shown in Fig. 8 and circular metal lined holes will 100 be provided for supporting the convolutions of conductor, the adjacent guards 21 forming, in effect, a series of metal eyelets.

One pair of strips of mica and two lengths 105 of mica wedges may be used for each rib 110

as already described in connection with Fig. 2 or several lengths of strips 14' and several lengths of mica wedges may be used for each rib as shown in Fig. 4. The terminals for the heating unit are indicated by the reference characters 22, 23, 24 and 25 which are connected to conductors 26, 27, 28 and 29, respectively.

While I have described my invention as embodying a concrete structure and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States, is:

1. An electric heater comprising a bare resistance element, means carrying said element, and a metal plate provided with openings separated by ribs covering said means.
2. An electric heater comprising a bare resistance element, means carrying said element, and a metal plate provided with openings separated by ribs supporting and covering said means.
3. An electric heater comprising a metal plate provided with openings separated by ribs vertically disposed, insulating strips

secured to the under side of said ribs and formed with holes, and a bare resistance element disposed within said holes, the ribs 35 covering said insulating strips.

4. An electric heater comprising a metal plate provided with openings separated by ribs, the ribs being formed with recesses on the under side, vertically disposed insulating strips formed with holes secured within said recesses and a bare resistance element disposed within the holes of said strips.

5. An electric heater comprising a metal plate provided with openings separated by 45 ribs, vertically disposed strips of insulating material formed with holes and secured to the under side of said ribs, and a resistance element disposed within said holes, the insulating strips being provided with slits 50 extending from said holes to the edge of the strips by which the resistance element may be inserted within the holes.

6. An electric heater comprising a metal plate provided with openings separated by 55 ribs, a bare resistance element carried beneath the plate by said ribs and insulated therefrom, and flanges secured to the under side of the plate adjacent to the resistance element.

In witness whereof, I have hereunto set my hand this sixth day of December, 1917.

ARTHUR FRANCIS BERRY.
